UNITED STATES PATENT OFFICE.

ARTHUR T. PRESCOTT, OF EAST ORANGE, NEW JERSEY, ASSIGNOR TO GEORGE E. FROTHINGHAM COMPANY, OF NEW YORK, N. Y., A CORPORATION OF NEW YORK.

DOOR AND HOISTING MECHANISM THEREFOR.

Application filed April 13, 1916. Serial No. 90,868.

To all whom it may concern:

Be it known that I, ARTHUR T. PRESCOTT, a citizen of the United States, and a resident of East Orange, county of Essex, and 5 State of New Jersey, have invented certain new and useful Improvements in Doors and Hoisting Mechanisms Therefor, of which the following is a specification, reference being had to the accompanying drawings, 10 forming a part thereof.

My invention relates to doors and has special reference to large, heavy doors for pier sheds, factories, and the like, which are arranged to swing in opening, from a 15 vertical plane to a substantially horizontal or an inclined plane above the door-opening.

One object of my invention is to provide a simple and durable door opening mechanism that shall be arranged not only to 20 hoist the door by an upward pull but also to exert a pull on the door near its upper end, to break it in and assist in swinging it both from and towards the door casing.

Another object is to provide a door opening mechanism adapted to exert forces tending to open the door and applied thereto 25 at points which move at varying speeds.

Another object is to provide an operating mechanism for swinging doors, comprising 30 a hoisting chain, a chain for pulling the top of the door away from or towards the casing, means such as a pocket sheave for actuating each chain, a driving means such as a hand chain, and a differential, compensating or lost motion mechanism for producing a continuous pull on each chain when 35 the operating mechanism is actuated although the chains are so connected to the door that they may be forced to move at 40 unlike speeds or one may be held stationary while the other continues its motion.

Another object is to provide means for exerting a positive pull upon the door near the top for both breaking in the door in 45 opening and holding it tightly against the casing when it is closed.

Another object is to provide a multi-section door, that is a door with two or more sections, having means for latching the door 50 closed at the top, means for latching the door sections together when they are overlapped, hoisting and actuating chains for opening the door, and differential gearing adapted to exert continuous pulls on both

chains while permitting the lower door section to be moved upwardly independently of the upper and locked thereto and both sections to be swung from the vertical to a substantially horizontal or an inclined plane.

Other objects of my invention will be set forth hereinafter, and in order that my invention may be thoroughly understood I will now proceed to describe the same in the following specification and then point out the novel features thereof in appended 65 claims.

Referring to the drawings:

Figure 1 is a front elevation of a two section door which is arranged and constructed in accordance with my invention and constitutes an embodiment thereof.

Figure 2 is a sectional elevation, taken on the line 2—2 of Figure 1.

Figure 3 is a partial section corresponding to Figure 2 but showing the door in its open 75 position.

Figure 4 is a sectional elevation on the line 4—4 of Figure 1 drawn to a larger scale.

Figure 5 is another sectional elevation, taken on the line 5—5 of Figure 1.

A plan view of the same parts is shown in Figure 6.

Figure 7 is a sectional plan view of the hoisting mechanism of the door, drawn to a larger scale.

Figure 8 is an end elevation of the same mechanism.

Figures 9 and 10 are sectional plans taken respectively on the lines 9—9 and 10—10 of Figure 1.

Figures 11, 12 and 13 are detail views showing parts of the structure of the previous figures.

Figures 14 and 15 are diagrammatic views corresponding to Figure 2, of modified door structures which also constitute embodiments of my invention.

The slip gear or sheave of Figure 15 is shown in section in Figure 16.

Still another modification of my invention is shown as applied to a single section door in Figure 17.

The structure of Figures 1 to 13 inclusive comprises a door casing having posts 15 and a lintel 16, a support or bracket 17 spaced 105 inwardly from the lintel, a door comprising sections 18 and 19, and a door opening mechanism 20.

The door posts are provided with guideways 21 which are adapted to cooperate with the lower section of the door, and guideways 22 which cooperate with rollers 23 located 5 near the lower corners of the upper section.

The upper section is provided with guideways 24 to receive the lower section which is adapted to slide on the upper section, and the door is suspended from brackets 25 10 above the door opening by links 26 which are connected to the guideways 24 on the upper door section.

The upper door section is provided with a latch 27 which, when the upper section is 15 closed, is held in a release position, by engaging with the lintel which holds it in opposition to a spring 28 (see Figures 11, 12 and 13). On the upper edge of the lower section is a catch or lug 65 which is adapted 20 to cooperate with the latch, the door sections being locked together by this means when they are overlapped and when the latch is disengaged from the lintel by the inward movement of the upper door section away 25 from the casing.

Pivottally mounted on the lintel is a lock 29 which is arranged to cooperate with an upwardly extending pin or projection 30 on the upper edge of the upper door section and 30 to extend into the path of the lower section which is provided with a projection 31 to release the lock.

The door opening mechanism comprises a transverse shaft 32 above the door opening, having a pair of spaced pocket sheaves 33 and 34 secured thereto near its ends. Co-operating with these pocket sheaves are hoisting chains 37 and 38 which are attached to projections 39 at the lower corners of the 40 lower door section, extend over the pocket sheaves and guide pulleys, and support, at their opposite ends, counterweights 40. A differential gearing 41 is located near the pocket sheave 34.

45 A sleeve or hollow shaft 42 is mounted on the shaft 32 and carries a pocket sheave or sprocket wheel 43 near the central plane of the door, and is coupled to a gear wheel 44 which forms a part of the differential gearing 41.

Mounted on the lintel is a pair of pocket sheaves or sprocket wheels 45 and 46, which are integral or secured together. The sheave 46 is operatively connected by a 55 chain 47 to the sheave or sprocket wheel 43 which is mounted on the hollow shaft 42. A continuous chain 49 is wrapped around the sprocket wheels 45 and 48 on the bracket 17 and is connected by any suitable means 60 such as a link 50 to a projection 51 from the upper door section 18.

The differential gearing comprises a disc 52 which is keyed to the shaft 32, a pair of pinions 53, and a gear wheel 54 in addition 65 to the gear 44.

The pinions 53 are on opposite sides of and mesh with the gear wheel 44 which is coupled to the hollow shaft 42 and are mounted on studs 55 of the disc 52.

They also mesh with the gear wheel 54 70 which is internally toothed to cooperate therewith.

The gear wheel 54 is also externally toothed and is driven by a pinion 56 which is operatively connected by gears 57 and 58 to 75 a shaft 59 to which a pocket sheave 60 is secured. The mechanism is actuated by a hand chain 61 suspended from the pocket sheave 60.

The differential gearing above described 80 in itself forms no part of my present invention and other well known differential gear structures may be employed.

The operation of the invention is as follows: Assuming that the door is closed as 85 shown in Figures 1 and 2, the lock 29 being active and holding the top of the door section against the casing, if the hand chain is operated to raise the lower door section, the shaft 59 and the pinion 58 are rotated 90 producing a rotation of the gear wheel 54 of the differential gearing. This rotation produces a rotation of the pinions 53 which tends to drive the gear wheel 44 and the disc 52 together with the shafts 42 and 32 to 95 which they are respectively secured. The shaft 32 is free to turn and is consequently rotated together with the pocket sheaves 33 and 34 secured thereto. The lower door section is thus elevated, and the counter- 100 weights 40 correspondingly lowered. However, the hollow shaft 42 cannot turn because the upper door section is held by the lock 29 and cannot be swung outwardly from the casing.

105 The differential gearing, however, puts a tension in the chains 47 and 49 which tends to throw the upper end of the upper door section away from the casing.

When the lower door section finally overlaps the upper section, the projection 31 at 110 its upper edge releases the lock 29 and the tension in the chains 47 and 49 causes the door to swing away from the casing. Thus, the tension serves as a very effective means 115 for breaking in the door at the top.

As the lock is released, the latch 27 engages the lug or catch 65 on the lower door section locking the two sections together. The hollow shaft 42 is now free to turn as 120 well as the shaft 32 and consequently both are turned and consequently both the hoisting chains 37 and 38 and the chains 47 and 49 are active. The hoisting chains elevate the lower end of the door which is now guided by the rollers 23 cooperating with the guideways 22 while the chains 47 and 49 pull the upper end of the door away from the casing.

125 Although the hollow shaft is released and 130

both shafts are active, they do not operate at the same speed because in swinging from a vertical to a horizontal position the upper end of the door first travels faster than the 5 lower end and afterward travels slower than the lower end. This is evident from the fact that the initial movement is comparable to an outward swinging of the upper end about the lower end as a pivot while 10 the final opening movement is comparable to the upward swinging of the lower end about the upper end as a pivot.

By the use of the differential gearing I am able to produce a constant pull on the 15 door, both at the top and at the bottom, one pull tending to hoist and the other tending to move the top of the door away from the casing, although the forces are applied to the door at different points which travel at 20 unlike speeds and without interfering with the initial independent movement of the lower section as it slides upon the upper.

In closing, the hand chain is operated in the reverse direction and the upper end of 25 the door is pulled in against the casing while the counterweights are raised, permitting the lower end of the door to descend. The lower door section tends to slide away from the upper but is held in place by 30 the latch 27.

When the upper section engages the casing, the latch 27 is released and the projection 30 is in position to be engaged by the lock 29 although the lock is held up by the 35 projection 31 of the lower section.

A continued actuation of the hand chain in the same direction after the upper section is against the casing at the top, produces a tension on the chains 47 and 49 40 which tightly pulls the upper section against the casing and holds it there. The shaft 32 however, is free to turn and the counterweights are elevated, permitting the lower section to descend independently of the up- 45 per section.

When the lower section has descended a short distance, the lock 29 engages pin 30.

My invention is very well adapted for multi-section doors, but is by no means limited in this regard.

Instead of the differential gearing which forms a part of the structure above described, other suitable means may be employed for compensating for the difference 55 in speed between the top of the door and the bottom of the door and for permitting the independent movement of the lower door section in case the door comprises more than one section. In order to indicate the 60 scope of my invention, I have shown modified structures in Figures 14 to 17 to which reference may now be had.

In Figure 14, 70 designates the lintel of the door which comprises an upper section 65 71 and a lower section 72; 73 and 74 are

guide pulleys, 75 is a floating sheave, 76 a door opening mechanism, 77 a hand chain and 78 and 79 counterweights.

A chain 80 is attached to the bottom section 73 at its lower end as indicated at 81 70 and extends upwardly over the guide pulleys 73 around the floating sheave 75, to the top of the upper door section where it is secured at 82.

Another chain section 83 extends from 82 75 over the guide pulley 74 to the counterweight 79. The counterweight 78 is suspended by a chain 84 which extends over a pocket sheave 86 of the door opening mechanism and is connected at its opposite end to 80 a yoke 85 in which the floating sheave 75 is mounted.

The operating mechanism in addition to the pocket sheave 86 comprises gearing 87 and a pocket sheave 88 with which the hand 85 chain 77 cooperates.

The operation of this modification is as follows: Assuming that the door is closed as shown in Figure 14, that the hand chain 77 is actuated to lower the counterweight and 90 pull in on the chain 84, the floating sheave 75 will approach the operating mechanism, and assuming that the upper door section 71 is locked as in the structure of the previous figures, the lower section 72 moves upwardly 95 and a tension is exerted on a section 80^a of the chain 80 tending to open the door at the top.

When the lower section overlaps the upper section and releases the lock, the continued 100 action of the hand chain produces a pull on the top as well as on the bottom of the door causing the door to break in at the top and swing into its open position.

The difference in speed between the top 105 and bottom is automatically compensated for by the floating sheave 75, which permits chain sections 80 and 80^a to adjust themselves.

After the top of the door is released, the 110 counterweight 79 is elevated and tends to pull the door closed. The counterweight 78 is, however, heavier and substantially balances the counterweight 79 and the door.

In closing the door, the hand chain is operated in the reverse direction so as to elevate the counterweight 78. The counterweight 79 now serves to pull the door closed and the weight of the door, of course, assists in this action. After the upper section 120 is closed against the casing, the weight of the lower section keeps the cable 80 in tension and the section is lowered as the counterweight 78 is raised.

The modification of Figure 15 corresponds 125 quite closely in general arrangement to the structure of Figures 2 and 3. It comprises a door opening mechanism 89 having an actuating chain 90, a pocket sheave 91, a hoisting chain or cable 92 connected to the 130

lower door section 72, extending over the pocket sheave 91 and connected at its opposite end to a counterweight 93. A chain or cable 94 is connected at 95 to the top of the upper door section 71 and is supported by a slip driving pulley 96 at one end and an idler pulley 97 is spaced at material distance from the plane of the door opening and corresponds to the sheave 48.

10 The slip driving pulley 96 is operatively connected in any suitable way to the door opening mechanism 89.

The slip pulley is shown in section in Figure 16 and comprises a disc 98 having a hub 99 keyed to a driven shaft 100, a disc 101 and a rim member 102 having an inwardly-extending, annular projection 103 which is clamped between the discs 98 and 101 by bolts 104 having spring washers 105.

20 The arrangement of parts is such that the sheave will transmit predetermined amount of power, but if the load or resistance exceeds a certain amount, the rim will slip relative to the hub.

25 The operation of this arrangement is as follows: Assuming the upper section 71 is locked at the top and the hand chain 90 is operated to open the door, the lower section 72 is raised and the counterweight 93 lowered. At the same time, the door opening mechanism 89 transmits power to the shaft 100 of the sheave 96 and thus produces a tension in the chain 94 tending to open the door. As soon as the upper section is

35 released and is free to move, the power is transmitted through the slip pulley 96 and the door is pulled inwardly at the top as well as hoisted by the chain 92 which is connected to the lower end.

40 The operative connection established between the mechanism 89 and the slip pulley 96 is such as to drive the top of the door at a maximum speed required in opening and consequently there will be certain slipping of the pulley to compensate for the speed variations hereinbefore described.

In Figure 17, I have shown still another modification which is better adapted for one piece doors. This arrangement comprises 50 an opening mechanism 106, a hand chain 107, a counterweight 108 which is suspended from a pocket sheave 109 by a chain 110, the opposite end of the chain being connected to the bottom of the door as indicated at 111.

55 A chain 112 is supported on the idler pulley 113, which is above the door opening, and a driving sheave 114 which is located to correspond to the idler 97 of Figure 15.

The chain 112 has a pair of resilient sections 115 and 116. Assuming that the door is closed when the hand chain 107 is actuated, the counterweight 108 is lowered and the door raised. There are two pulls exerted on the door: One, on the bottom and one 60 on the top, the forces acting at an angle to

each other so that one breaks in the door at the top and assists in pulling it open, while the other elevates the lower end which is guided vertically in a well known manner.

As hereinbefore explained, the top of the door does not travel at a constant speed or at the same speed as the bottom of the door and while the driving sheave 114 is connected to the same mechanism 106 which exerts an upward pull at the bottom of the door, the springs 115 and 116 compensate for this difference in speed.

Various other modifications may be effected within the spirit and scope of my invention, and I intend that only such limitations be imposed as indicated in the appended claims.

What I claim is:

1. The combination with a door arranged to swing out of a vertical closed position to a non-vertical open position above the door opening, of a door hoisting connection acting in the plane of the door opening, a connection for moving the top of the door from and towards the plane of the opening, said connections having different rates of movement and including means for compensating for the difference in movement of the connections and means for actuating said connections.

2. The combination with a door arranged to swing out of a vertical closed position to a non-vertical position above the door opening, of a hoisting chain acting in the plane of the door opening at one rate of movement, a chain arranged to move the top of the door from and towards the plane of the opening at another rate of movement, means between the chains for moving them at different rates of speed including mechanism for compensating for the differences in the movement of the chains and means for actuating said means.

3. The combination with a door arranged to swing out of a vertical closed position to a non-vertical open position above the door opening, of a hoisting chain acting in the plane of the door opening at one rate of movement, a chain arranged to move the top of the door from and towards the plane of the opening at another rate of movement, and a single means for moving the two chains, including gearing for compensating for the difference in movement of the two chains, and means for actuating said single means.

4. The combination with a door arranged to swing out of a vertical closed position to a non-vertical open position above the door opening, of a hoisting mechanism therefor, and means connected with the hoisting mechanism for moving the door laterally at the top during both the closing and opening of the door.

5. The combination with a door arranged

- to swing out of a vertical closed position to a non-vertical open position above the door opening, of a positively actuated hoisting mechanism connected to the door at the bottom, means for exerting a substantially horizontal pull at the top of the door to move it to and from the casing, and an interposed connection between the hoisting mechanism and said means, whereby said means is driven.
6. The combination with a door casing comprising side posts and a lintel defining the door opening, of a door comprising an upper section, means for suspending the upper section to permit it to swing out of a vertical closed position to a non-vertical open position above the door opening, a lower door section arranged to overlap the upper section and cooperate therewith, hoisting means connected with the lower part of the lower door section, other means connected with the upper door section arranged to exert a lateral pull upon the door sections at the top thereof for both opening and closing the door, including means for compensating for the difference in movement between the points of connection of said hoisting means and said other means while the two sections are moving together, a latch on the upper section arranged to be engaged by the lintel and released by the closing of the upper section against the casing, for locking the sections together when they are overlapped, and means for actuating said latch by the top of the door section's swinging away from the casing.
7. The combination with a door arranged to swing out of a vertical closed position to a non-vertical open position above the door opening and comprising a plurality of sections, a latch near the top of the upper door section arranged to be released by the closing of the upper door section, a cooperating fastener on the lower section arranged to be engaged by the latch when the door sections are overlapped and the top is swung away from the casing, and means for actuating said latch by the top of the door section's swinging away from the casing.
8. The combination with a door casing comprising side posts and a lintel defining the door opening, of a door comprising an upper section, means for suspending the upper section to permit it to swing out of the vertical closed position to a non-vertical open position above the door opening, a lower door section arranged to overlap the upper section and cooperate therewith, means arranged to be released by the closing of the upper section against the casing, for locking the sections together when they are overlapped, and means for actuating said latch by the top of the door section's swinging away from the casing.
9. The combination with a door casing comprising side posts and a lintel defining the door opening, of a door comprising an upper section, means for suspending the upper section to permit it to swing out of a vertical closed position to a non-vertical open position, above the door opening, a lower door section arranged to overlap the upper section and cooperate therewith, a latch on the upper section arranged to be engaged by the lintel and released by the closing of the upper section against the casing, for locking the sections together when they are overlapped, and means for actuating said latch by the top of the door section's swinging away from the casing.
10. The combination with a door arranged to swing out of a vertical closed position to a non-vertical position above the door opening, of a hoisting element acting in the plane of the door opening at one rate of movement, an element arranged to move the top of the door from and towards the plane of the opening at another rate of movement, means between the elements for moving them at different rates of speed including mechanism for compensating for the differences in the movement of the elements and means for actuating said means.
11. The combination with a door arranged to swing out of a vertical closed position to a non-vertical open position above the door opening, of a hoisting element acting in the plane of the door opening at one rate of movement, an element arranged to move the top of the door from and towards the plane of the opening at another rate of movement, and a single means for moving the two elements including gearing for compensating for the difference in movement of the two elements, and means for actuating said single means.

In witness whereof, I have hereunto set my hand this 24th day of March, 1916.

ARTHUR T. PRESCOTT.
